Jeanette Meng Nakagawa(57) **CLAIM**

The ornamental design for an iPhone® separate clip mobile power supply, as shown and described.

DESCRIPTION

FIG. 1 is a perspective view of an iPhone® separate clip mobile power supply showing my new design;

FIG. 2 is a bottom view thereof;

FIG. 3 is a top view thereof;

FIG. 4 is a front view thereof;

FIG. 5 is a right side thereof;

FIG. 6 is a left side thereof; and,

FIG. 7 is a back side view thereof.

The broken lines indicate unclaimed portions of the article that form no part of the claimed design.

The iPhone® separate clip mobile power supply forming part of the claimed design is a registered trademark of Apple Inc. Corporation.
